TIMED DUMP BAILER

George H. Ennis, Long Beach, Calif., assignor of
one-half to Robert V. Funk, Long Beach, Calif.Application September 13, 1935, Serial No. 40,437
Renewed March 19, 1938

12 Claims. (Cl. 161—7)

My invention relates to an apparatus whereby a dose or quantity of material may be deposited in a well or bore hole. My invention is of utility in the various arts, but it is of particular value in the oil producing industry and may be used to a very marked advantage for depositing electrolyte in a well in order to prepare the well for testing as covered by my patent entitled Method and apparatus for determining the location of water strata in wells, No. 1,786,196, issued December 23, 1930.

I believe my invention to be broadly new not only in its entirety but also in the several sub-combinations and the various novel elements which I have invented. In order to illustrate the principle and the advantages and features of my invention, I will describe and disclose hereinafter certain forms of my invention, and I will describe its use in connection with the depositing of electrolyte in an oil well. It should be understood, however, that my invention is not to be limited to the precise details of construction which I have chosen to disclose herein nor to the particular use which I shall refer to.

In my patent referred to above I have disclosed a method of determining the point or points at which water enters a well. In order to make a test, as pointed out in my prior patent, it is only necessary to deposit the electrolyte at those points where the water leakage occurred. This point of entrance of the water may be at any point in the well ranging from the extreme bottom of the well to the upper regions thereof. The process referred to involves the depositing of an electrolyte in the well at the point where it is suspected that the water is entering the well. If, upon completing the test, it is found that the water leakage occurred at the point believed, it is not necessary to place electrolyte in any other part of the well. It will be seen, therefore, that it is highly desirable to have a device which is capable of depositing or delivering electrolyte to the well at the precise desired point where the test is to be made regardless of whether this location is at the bottom of the well or at any other elevation. In view of the fact that I could not find a satisfactory device in the prior art I invented the apparatus which constitutes the subject matter of my present invention.

It is an object of my invention to provide an apparatus for delivering a dose or charge of material into the well as any point from the bottom of the well to the upper regions thereof.

It is a further object of my invention to provide an apparatus of the character mentioned in

which the releasing of the material or the delivery of the material from the apparatus into the well is entirely independent of the walls of the well or any relative movement between the apparatus and the walls of the well or the bottom thereof.

It is another object of my invention to provide an apparatus of the character referred to in which the charge is automatically released from the apparatus and delivered into the well.

It is a still further object of my invention to provide an apparatus of the general character referred to heretofore in which the material is discharged after a predetermined period of time.

It is another object of my invention to provide an apparatus of the general character referred to in which the valve which is operable to discharge the material from the apparatus into the well is automatically opened upon the lapse of a predetermined period of time.

An additional object of my invention is to provide an apparatus of the general character referred to having a time control means which may be set to open the discharge valve of the apparatus upon the lapse of any predetermined period of time.

It is another object of my invention to provide an apparatus of the character referred to in the preceding paragraph in which the time means is set while the apparatus is at the surface of the ground and in which the time means operates an electrical means which in turn opens the discharge valve of the apparatus.

It is a still further object of my present invention to provide an apparatus of the character defined in the second preceding paragraph in which the time means is a hydraulic apparatus which is set at the surface of the ground, and which after a predetermined period of time operates mechanism for opening the discharge valve of the apparatus.

A still further object of my invention is to provide an apparatus of the general character referred to heretofore in which the discharge valve is held in closed position by apparatus which may be operated from the surface of the ground at any desired time, and which is operated entirely independent of the walls of the well or any relative movement between the apparatus and the well.

In the detailed description of different forms of my invention which is to follow, I will describe various additional objects, features and advantages of my invention.

In the accompanying drawings I have illus-

trated certain forms of my invention, and in these drawings:

Fig. 1 is a diagrammatic view somewhat schematic in character, illustrating the utility of my invention.

Fig. 2 is a vertical sectional view through one form of the automatic valve control mechanism of my invention.

Figs. 3, 4, 5, 6, and 7 are sectional views taken 10 through Fig. 2 as indicated by the sectional lines and arrows bearing the numerals corresponding to the different views.

Fig. 8 is a vertical sectional view of schematic character through a second form of valve control 15 means of my invention.

Figs. 9, 10, 11, 12, and 13 are sectional views of Fig. 8 taken as indicated by the lines and arrows bearing corresponding numerals.

Fig. 14 is a sectional view showing another type 20 of valve control mechanism of my invention.

Fig. 15 is a vertical sectional view of schematic character showing still another form of valve control mechanism which I have devised.

Referring to Fig. 1, the numeral 11 represents 25 an oil well in which a casing or pipe 12 has been installed. At the lower end of this oil well is a series of formations 14, 15, 16, 17, and 18. Adjacent these formations is a screen pipe or strainer pipe 20 which is ordinarily secured to the lower 30 end of the casing 12.

In order to make a test of the well in accordance with the method disclosed in my Patent No. 1,786,196 referred to heretofore, it is necessary to place an electrolyte in the well from the bottom 35 of the well to approximately a level indicated by the line 22, which is above the perforations in the casing.

In order to so deposit an electrolyte in the well I may use an apparatus for delivering a charge of 40 material in the well which may be in the form of any of the different types of apparatus illustrated in Figs. 2 to 14 inclusive or may be in other forms incorporating the principles of my invention which constitute the subject matter of the present application. In Fig. 1 I have shown an apparatus 25 which represents my invention. This apparatus is secured to the lower end of a cable 26 and is lowered into the well into a position approximately as shown in Fig. 1. After the apparatus 25 has 50 reached this position the discharge valve of the apparatus will be automatically opened and the contents thereof will be thereupon discharged into the well and will fill the well to the level 22. It is obvious, of course, that if the space in the well is 55 quite large it may be necessary to deliver a number of charges of electrolyte which is done by repeating the operation just described. After the electrolyte has been delivered into the well into the desired position the well may then be tested.

Having outlined the general procedure employed in my invention when it is used for the purpose of delivering electrolyte into a well, I will now describe the details of construction of different forms of the invention incorporating the essential features thereof.

Referring to Figs. 2 to 7 inclusive, the upper portion of the apparatus 25 is in the form of a shell 30 which provides a reservoir 31 in which the charge of material is retained. The lower 70 end of the shell 30 is provided with a seat member 32 having an outlet passage 33 which is adapted to be closed by a valve 34 which is held against the seat 32 by a latch means which I will now describe.

It will be seen that projecting downwardly from

the shell 30 is a tubular member or housing 36, and this tubular member 36 houses the various apparatus which is employed to control the operation of the valve 34.

The valve 34 has a short stem 37 which fits into an upper section 38 of a body, which body also includes a lower section 39. The stem 37 is loosely supported in an opening 40 of the upper section by means of a pin and slot arrangement 41 which includes the pins supported by the upper section 38 which fit into slots formed in the stem 37. In the lower part of the cavity 40 is a spring 43 which forces the stem 37 and the valve 34 upwardly. The body comprising the upper and lower sections 38 and 39 is supported in a fixed position, as will be described later, and the spring 43 then constitutes a means for resiliently urging the valve 34 against the seat 32. In order to provide for adjustment, which may be required in order to properly position the valve 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350

The body which supports the valve 34 is locked or retained in the position shown in full lines in Fig. 2 by a latch means which I will now describe. The lower part of the section 39 is provided in the form of a depending annular or cylindrical wall 50. This wall 50 has a plurality of openings 51 formed in it which are preferably equally spaced around the circumference of the wall 50. These openings 51 are of such a size as to retain latch members in the form of balls 52. Formed in the housing 36 is an annular channel 53 into which the balls 52 may extend when the body is in the position shown in full lines in Fig. 2 and when the balls are held in the positions shown by means of a retaining member 54. It will be seen that when the balls 52 are held in the positions shown that they form a locking means between the annular wall 50 and the housing 36, and therefore serve to lock the body in the position shown in full lines in Fig. 2. When the body is so positioned the parts or sections 38 and 39 thereof are so adjusted that the valve 34 engages the seat 32 and the spring 43 is compressed so that there is a resilient force urging this valve against its seat.

The retaining means 54 includes a head 55 having a cylindrical portion 56 which is of such a size that when it is positioned adjacent the balls 52 it holds the balls 52 so that they are engaged in the channel 53. Above the cylindrical wall 56 is a recess 57. Above the recess 57 is a flange 58, and below the cylindrical wall 56 is a similar flange 59 which limits the movement of the retaining means relative to the balls 52 and the body. When the retaining means is lowered relative to the valve 34 of the body, as illustrated by dotted lines 60, the balls 52 are free to move inwardly so that they are disengaged from the channel 53. This is effective in unlatching the body, and it will thereupon drop into a depressed position as indicated by dotted lines 62. It will be seen that this action lowers the valve 34 from closed position and allows the material in the chamber 31 to flow through the outlet passage 33 into the upper end of the housing 36 and outwardly into the well through openings 63 provided in the housing 36.

For the purpose of controlling the operation of the retaining means 54 I provide mechanism for holding the retaining means in the position shown in full lines in Fig. 2 or for permitting the retain-

ing means to move downwardly relative to the section 38 into the position indicated by the dotted lines 60. The mechanism which I provide is constructed as follows. Extended downwardly 5 from the head 55 of the retaining means 54 is a stem 65 having a nut 66 screwed on the lower end thereof which is provided with left hand threads. This nut 66 has outwardly projecting arms 67 which extend into vertical slots 68 formed in a 10 release sleeve 69. The upper ends of the slots 68 have horizontal portions 70 so as to provide shoulders 71 upon which the arms 67 may rest, as shown in Fig. 5, when the retaining means is to be held in the position shown in full lines in 15 Fig. 2. The nut 66 is threaded on the stem 65 so that it can be adjusted into a suitable position so that when the arms 67 rest on the shoulders 71 the cylindrical portion 56 of the head 54 will be adjacent the balls 52, thus locking the body 20 in place. The head of the retaining means is caused to move into the position indicated by dotted lines 60 by rotating the release sleeve 69 in a clockwise direction when viewing Fig. 5. This brings the vertical portions of the slots 68 25 into alignment with the arms 67 and rotates the nut 66 on the threaded stem 65 so that the nut 66 pulls the entire retaining means 54 downwardly to the position indicated by the dotted lines 60. When this occurs the balls 52 move 30 inwardly as previously explained, and the entire assembly, including the body and the valve 34, then drops downwardly as a whole and may rest in the position indicated by the dotted lines 62. As the entire assembly drops, the projections 35 67 of the nut 66 move downwardly in the vertical slots 68. In order to provide a support for the parts in lowered position I provide a rubber bumper 74 which may be engaged by the lower end of the stem 65 when the parts drop as just 40 explained.

For the purpose of rotating the release sleeve 69 I provide this release sleeve with a downwardly projected shaft 75 which has a spring 76 associated with it which is adapted to rotate the shaft 45 75 and the release sleeve 69 in a clockwise direction when viewing Fig. 5.

For the purpose of locking the release sleeve in a position to hold the nut 66 in the position shown in Fig. 2, I provide a brake construction 50 including a toothed wheel 77 which is locked from rotation by means of a spring loaded pawl 78. The wheel 77 is mounted on a shaft 79 which is in turn connected to the shaft 75 through a gear and shaft arrangement indicated by the numeral 55 80. When the brake arrangement is in the position shown in full lines in Fig. 2, the shaft 75 and release sleeve 69 are locked in the positions shown. However, upon retracting the pawl 78 into a position indicated by dotted lines 81, the wheel 77 is 60 released and the spring may then rotate the shaft and release sleeve so that the parts will be operated as pointed out heretofore. The release sleeve 69 may be reset after actuation by any suitable means such, for example, as a bevel gear 82 65 secured to the shaft 75 adapted to be engaged by a crank mechanism shown in dotted lines in Fig. 2, and which is used only during the resetting operation. The numeral 83 represents a gear secured to the inner end of a crank 84. The 70 crank 84 may be held in a suitable position to engage the gear 83 with the gear 82 by means of a block 85a adapted to fit in an opening 85b provided in the housing 36.

The pawl 78 is moved into disengaged position by time control mechanism which I will

now describe. Supported in the lower end of the housing 36 is a solenoid consisting of a coil 85 and a core 86 adapted to be pulled into the coil 85 when the coil is energized. This core 86 is connected by a link 87 to the pawl 78 so that when the core is pulled downward the pawl is disengaged from the toothed wheel 77. For the purpose of energizing the solenoid coil 85 I provide an electrical circuit including battery means 88 and a time control switch 90. The time control switch 90 has a stationary contact 91 and a movable contact 92 which is operated by a suitable clockwork which is not illustrated in detail because such mechanisms are well known in various industries. The movable contact 92 15 may be set into any desired position relative to the stationary contact 91 by means of a setting knob 94 so that the time before engagement of the movable contact and stationary contact may be any desired period of time. The movable contact 92 is connected by means of a wire 96 to the housing 36 and is therefore grounded. The stationary contact 91 is connected by a wire 97 to the battery 88, and the battery 88 is connected to the solenoid coil 85 by means of a conductor 20 98. The other end of the solenoid coil 85 is connected by a wire 99 to the housing 36, thus forming a complete circuit. It will be seen that when the movable contact 92 is moved into engagement with the stationary contact 91 that the solenoid 25 coil 85 is energized, thus pulling the core 86 downward and thus moving the pawl 78 into the position indicated by dotted lines 81.

For simplification I have diagrammatically illustrated certain of the parts of my invention. It should be understood, however, that the various parts which are diagrammatically illustrated are either well known in the industry or may be readily made by any skilled mechanic. I have purposely left out certain details of construction of 40 various parts which may be employed to protect the mechanism of my invention. This has been done since no invention is involved in such parts which I have purposely left from the drawings, and it is believed that in this way the construction is greatly simplified and therefore may be 45 more readily understood by those skilled in the art who, at their own volition, may add what other details of construction they desire.

It is believed that the full operation of the 50 device just described is readily understood. When the apparatus 25 is at the surface of the ground the time control means 90 is set so that the circuit will be closed after a predetermined period of time, this period of time usually being 55 that required to lower the device into the well plus a few minutes to allow for any delay which might be occasioned. The apparatus is then lowered into the well into a position shown in Fig. 1 60 and is supported in the position shown in Fig. 1 at the time the contacts 91 and 92 are closed. The charge of material in the chamber 31 is then discharged. The manner in which the material is discharged, of course, depends upon the details of construction of the means for ejecting 65 the material from the apparatus when the valve 34 is opened. In some types of apparatus it is necessary to raise the apparatus slowly in order that the material in the chamber 31 will be displaced by the well fluid entering the upper end 70 of the chamber 31 which is open.

The opening of the valve 34 is accomplished by the apparatus which I have just described and in accordance with the method of operation which I have described in detail, and which I will 75

briefly point out in full as follows. When the contacts 91 and 92 are engaged the circuit is completed and the solenoid coil 85 energized. This depresses the core 86 and pulls the pawl 78 into dotted line position 81. This releases the brake on the shaft 75 and thus allows the spring 76 to rotate the shaft 75 and the release sleeve 69 in clockwise direction. This first causes a rotation of the sleeve relative to the nut 66 and causes the vertical portions of the slot 68 to be brought into alignment with the arms 67 and then rotates the nut 66 on the stem 65 to pull the retaining member down into position indicated by dotted lines 60. When the parts are in this position the balls 52 may move inwardly, and when these balls 52 move inwardly the body, including the upper and lower sections 38 and 39, is released from the housing 36 and is then free to fall downwardly into the positions indicated by dotted lines 62 in Fig. 2. This lowers the valve 34 and allows the charge in the chamber 31 to flow downwardly through the outlet passage 33 and the opening 63 in the housing 36 into the well.

The valve is reset into closed position as follows. The circuit to the solenoid coil 85, if it has not already been broken, is broken so that the pawl will be returned to full line position in Fig. 2. The body is then moved by inverting the device, for example to the position shown in full lines in Fig. 2 and at that time the retaining member is in the position relative thereto, as shown by dotted lines 60, the balls being in inward position. When the body is in this position the balls are substantially in alignment with the groove 53, and thereafter the retaining member is moved into the position shown in full lines by rotation of the release sleeve 69 in anti-clockwise direction so as to first bring the shoulders 71 into position facing the arms 67 and then rotate the nut 66 on the stem 65 to move the head from its dotted line position to its full line position. This may be done by the use of the cranking mechanism illustrated by dotted lines in Fig. 2. It is possible to rotate the shaft due to the fact that the toothed wheel 77 is provided with teeth which are inclined and therefore may move past the engagement end of the pawl 78 in the direction required to rotate the shaft and release sleeve 69 to reset. If necessary, the upper section 38 may be rotated relative to the lower section 39 in order to obtain a full and positive resilient feeding of the valve 34. Furthermore, if desired, in order to relieve any pressure on any of the parts during resetting, the upper section 38 may be screwed rearwardly relative to the lower section 39. After the parts have all been set as described, the section 38 may then be rotated relative to the section 39, thus raising the parts so as to bring the valve 34 into resilient engagement with the seat 32. When it is desired to lower the device into the well, the time means may be wound up and set as previously described so that the contacts will be closed after a predetermined period of time.

In the form of my invention shown in Figs. 8 to 13 inclusive I illustrate a closure valve 100 which engages a seat 101 in order to close an outlet passage 102 of the chamber 103. The valve 100 is supported by a body 105 in a manner similar to that in which the valve 34 is supported, there being pins 106 supported by the body 105 which extend into grooves 107 provided in the stem 108 of the valve 100, and there also being a

compression spring 109 urging the valve 100 in an upward direction.

The body 105 is locked in the position shown in Fig. 8 by a latch means which consists of a plurality of latch members or balls 111, the inner parts of which rest in an annular groove 112 formed in the body 105. The outer portions of the balls 111 are in engagement with an internal cylindrical wall 114 of a connector member 115 which forms a part of the housing 116 of the apparatus. For the purpose of retaining the balls or lock members in the positions shown in full lines in Figs. 8 and 10, I provide a retaining means which includes a retaining sleeve 118. This retaining sleeve 118 has openings 118a through which the balls 111 extend. When it is desired to open the valve 100, this is done by rotating the retaining means in a clockwise direction. This moves the balls 111 into such a position that they may move outwardly into recesses 119 which are formed in the connector member 115 at an elevation which is in the same horizontal plane as the annular groove 112 of the body 105. When the balls move outwardly into the recesses 119 they are disengaged from the annular groove 112, and therefore the body 105 is permitted to move downwardly. This removes the valve 100 from its seat so that the material in the chamber 103 may flow through the outlet passage 102 and through openings 121 into the well. The retaining means is operated or moved into a released position by means of a coil spring 122, one end of which is secured to a wall 123 of the housing 116, as illustrated at 124, and the other end 125 of the spring 122 is connected to a stem or shaft 126 which extends downwardly from the retaining shell 118 and which has its lower end received by a bearing 127 of the wall 123 of the housing 116. The retaining means, however, is ordinarily restrained from rotation by means of a brake which is illustrated best in Figs. 8, 11, and 12. Secured to the upper portion of the shaft 126 is a brake drum 130 having a groove 131 formed in it. Received in the groove 131 is a brake band 132. One end of the brake band is pivotally secured at 133 to the housing 116 and the other end of the brake band is connected to an operating bar 134. The operating bar 134 is supported by the walls of the connector 115 defining an opening 135 through which the operating bar 134 extends, and also by the supporting lug 136. The operating bar 134 extends through an opening 137 formed in the free end of the brake band 132, and the lower end of this operating bar is widened as illustrated at 138. When the widened portion of the bar extends through the opening 137 it will be seen that the free end of the brake band is pulled away from the brake drum 130 so that the brake band is applied to the brake drum and the retaining means is locked from rotation. However, when the operating bar is moved downwardly so as to bring a narrow portion 140 thereof into a position within the opening 137 the free end of the brake band 132 may move so as to release the brakes, and at this time the retaining means may be rotated by the action of the spring 122.

For the purpose of operating the operating bar I provide a tension spring 142 at its lower end which exerts a downward force. The operating bar, however, is retained in the position shown in Fig. 8 by means of a holding link 143 which, in this form of my invention, is a fusible link which may be melted by the passage of an electric current through it, and when this occurs the spring 75

142 pulls the operating bar 134 downwardly so as to release the brakes.

For the purpose of melting the fusible link 143 I provide an electric circuit including a source of energy in the form of a battery 146 which is connected by a wire 147 to a movable contact 148. The movable contact is adapted to be engaged, by means which I will hereafter describe, with a stationary contact 149 which is connected by 10 means of a conductor 150 to the lower end of the fusible link 143. The upper end of the fusible link 143 is connected by a conductor 151 to the housing 116 which acts as a ground, the battery 146 being also grounded to the housing. When 15 the movable contact 148 is caused to engage the stationary contact 149 the circuit is completed and the electricity will flow through the fusible link 143, thus melting it, and when the fusible link is melted the operating member 134 will be moved 20 downwardly as previously described, with the result that the retaining means is rotated so that the balls 111 are moved into a position that they may move outwardly into the recesses 119.

For the purpose of closing the switch in the 25 circuit; that is, causing the movable contact 148 to engage the stationary contact 149, I provide time control means which in this form of my invention is a hydraulic means. This hydraulic means is shown as comprising a chamber 160 which is formed near the lower end of the housing 116. Within this chamber 160 is a cylinder 161 having a piston 162 which is movable therein. This piston 162 is engaged by a spring 163 which tends to move it in an upward direction. 30 The piston 162 is provided with a passage 164, which passage is closed by a valve 165 which permits a flow of fluid only in a direction toward the chamber 166 provided by the cylinder 161. The cylinder 161 is provided with a small opening 168 which connects the chamber 166 with the chamber 160. The chamber 160 is filled with a liquid, such as oil, glycerine, etc. The piston 162 may be depressed by means of a longitudinal movable member 168' which is engageable at its lower end 35 with a flange 169 of the piston 162. When the piston is depressed the liquid in the chamber 160 will flow through the passage 164 and into the chamber 166. The spring 163 then urges the piston 162 upwardly, the valve 165 closing at this 40 time. This forces the liquid through the opening 168. The rate of movement of the piston 162 in an upward direction depends upon the rate of flow of the liquid through the opening 168. When the piston reaches its uppermost position 45 the flange 169 is adapted to engage the movable contact 148 and to cause it to engage the stationary contact 149, and in this manner the circuit to the fusible link 143 is closed. It will be seen that when the piston is depressed the length 50 of time before the circuit to the fusible link will be closed depends upon the distance that the piston 162 is depressed. It is therefore possible to calibrate the upper end of the actuating rod 168' as indicated at 170, and in this way the length 55 of time before the fusible link will be melted may be accurately controlled, and in this way the operator will know how long a lapse of time there will be before the valve 160 will be opened.

The operation of this device is as explained 60 heretofore, but is explained in its entirety briefly as follows. The piston 162 is depressed so that there will be a desired lapse of time before the contact 148 is brought into engagement with the contact 149. The device is then lowered into the 65 well and properly positioned. When the length of 70

time required for the piston 162 to move into its upper position has expired, the circuit to the fusible link 143 will be completed and this link will be melted. This will allow the spring 142 to pull the operating bar 134 downward. When this occurs the brake band 132 is released from the brake drum 130 and the spring 122 will then rotate the retaining means. The retaining means then rotates the balls 111 so that they may fall into the recesses 119. This disengages the balls from the body 105 and the body may fall into a lowered position, thus removing the valve 160 from its seat.

In order to reset the device it is necessary to return the body to its original position and then 15 to rotate the retaining means. The brake must then be set by returning the operating member into the position indicated in full lines in Fig. 8. This is done by raising the operating member and replacing the used fusible link with a new link 20 which holds the operating member in the desired position. During this time, of course, the circuit to the fusible link must be broken. When it is desired to use the device in a well the piston is then moved downwardly by means of the rod 168' 25 to the desired position so that the desired lapse of time before actuation may be obtained.

In Fig. 14 I have illustrated a form of my invention which is not wholly automatic in its operation, but which may be operated from the 30 surface of the ground. In this form of my invention I do not use the hydraulic time means for closing a circuit including the fusible link. In place of this mechanism I use an electric circuit consisting of wires 180 and 181 which may be extended to the surface of the ground through the cable 26 which supports the apparatus 25. At the surface of the ground there is a battery 182 and a manually operable switch 183 included in the circuit. When the switch 183 is closed the 40 electrical circuit is completed and the fusible link 143 is melted, thus allowing the spring 142 to depress the operating bar 134, and in this manner the valve 160 may be removed from its seat. It will be seen that in this form of the invention 45 there is no time device to be set. The apparatus may be lowered into the well into any position desired, and whenever it is desired to deliver the material to the well it may be done by manually closing the switch 183.

In the form of my invention shown in Fig. 15 the electrical control means which determines the position of the operating member 134, as shown in Fig. 8 has been eliminated and an operating member 134a has been provided which is directly actuated by the hydraulic time device. Therefore, in Fig. 15 the lower end of the operating member 134a is provided with an extension 190 which extends downwardly into the chamber 160. The lower end of the extension 60 190 is adapted to be engaged by the flange 169 of the piston 162 when this piston approaches its upper position. When the extension 190 is engaged the operating member 134a is moved upward and the brake band 132 is released in the 65 same manner that it is released in the form of the invention shown in Figs. 8 to 13 and in Fig. 14. In the form of invention shown in Fig. 15 all of the parts operate in the same manner as described in connection with Figs. 8 to 13 inclusive except that the electrical circuit has been eliminated and the operating member 134a is directly operated by the hydraulic time means.

I claim as my invention:

1. In an apparatus of the class described, for 75

delivering a charge of material into a well, and having a reservoir for holding the material and a valve operable to discharge the material from said reservoir, the combination of: valve-opening means for opening said valve; and time means which may be set to actuate after a lapse of time to actuate said valve-opening means.

2. In an apparatus of the class described, for delivering a charge of material into a well, and having a reservoir for holding the material and a valve operable to discharge the material from said reservoir, the combination of: spring controlled valve-opening means for opening said valve; and time means which may be set to actuate after a lapse of time to release the spring of said valve-opening means in order to actuate said valve-opening means.

3. In an apparatus of the class described, for delivering a charge of material into a well, and having a reservoir for holding the material and a valve operable to discharge the material from said reservoir, the combination of: latch means whereby said valve may be latched in closed position or permitted to assume an opened position; latch-retaining means whereby said latch means may be retained in latched or unlatched position; and time means which may be set to operate after a predetermined lapse of time to operate said latch-retaining means to release said latch means.

4. In an apparatus of the class described, for delivering a charge of material into a well, and having a reservoir for holding the material and a valve operable to discharge the material from said reservoir, the combination of: latch means whereby said valve may be latched in closed position or permitted to assume an opened position; latch-retaining means whereby said latch means may be retained in latched or unlatched position; and electrically operated releasing means comprising a time means which may be set to operate after a predetermined lapse of time to operate said latch-retaining means to release said latch means.

5. In an apparatus of the class described, for delivering a charge of material into a well, and having a reservoir for holding the material and a valve operable to discharge the material from said reservoir, the combination of: latch means whereby said valve may be latched in closed position or permitted to assume an opened position; latch-retaining means whereby said latch means may be retained in latched or unlatched position; and hydraulically operated time means which may be set to operate after a predetermined lapse of time to operate said latch-retaining means to release said latch means.

6. In an apparatus of the class described, for delivering a charge of material into a well, and having a reservoir for holding the material and a valve operable to discharge the material from said reservoir, the combination of: a valve-supporting body which supports said valve in closed or opened position; latch means for said valve-supporting body for holding said valve in closed position; retaining means for retaining said latch means in a latched position; release means for said retaining means which is operable to release said retaining means in order to unlatch said latch means and move said valve-supporting body into opened position; and time-delay means for actuating said release means.

7. In an apparatus of the class described, for delivering a charge of material into a well, and having a reservoir for holding the material and

a valve operable to discharge the material from said reservoir, the combination of: a valve-supporting body which supports said valve in closed or opened position; latch means for said valve-supporting body for holding said valve in closed position; retaining means for retaining said latch means in a latched position; release means for said retaining means which is operable to release said retaining means in order to unlatch said latch means and move said valve-supporting body into opened position; a brake for restraining said release means from operating; and time-delay means for releasing said brake.

8. In an apparatus of the class described, for delivering a charge of material into a well, and having a reservoir for holding the material and a valve operable to discharge the material from said reservoir, the combination of: a valve-supporting body which supports said valve in closed or opened position; latch means for said valve-supporting body for holding said valve in closed position; retaining means for retaining said latch means in a latched position; release means for said retaining means which is operable to release said retaining means in order to unlatch said latch means and enable movement of said valve-supporting body into opened position; a brake for restraining said release means from operating; and electrically operated releasing means comprising time-delay means for releasing said brake.

9. In an apparatus of the class described, for delivering a charge of material into a well, and having a reservoir for holding the material and a valve operable to discharge the material from said reservoir, the combination of: a valve-supporting body which supports said valve in closed or opened position; latch means for said valve-supporting body for holding said valve in closed position; retaining means for retaining said latch means in a latched position; release means for said retaining means which is operable to release said retaining means in order to unlatch said latch means and enable movement of said valve-supporting body into opened position; a brake for restraining said release means from operating; and brake release means for releasing said brake.

10. In an apparatus of the class described, for delivering a charge of material into a well, the combination of: a reservoir for holding the material, said reservoir having a valve opening; a valve member for closing said opening; latch means for holding said valve member in such position that it will close said opening; power means operative to move said latch means out of its holding position; and a time delay control means carried by said apparatus in operative relation to said power means for governing the operation of said power means so that the opening of said valve member may be had at a desired time.

11. In an apparatus of the class described, for delivering a charge of material into a well, the combination of: a reservoir for said material having an opening at the lower end thereof; a tubular member extending downwardly from the lower end of said reservoir; a valve member in the upper part of said tubular member adapted to be moved into a position for closing said valve opening of said reservoir; latch means adapted to be moved outwardly from said valve member into engagement with said tubular member to hold said valve member in raised position; a latch holding member having a latch holding position wherein it holds said latch means in engagement with said tubular member and a re-

tracted position wherein it releases said latch means, said latch holding member having a threaded part projecting downwardly therefrom; a nut member engaging said threaded part; power means operative to rotate said nut member whereby to move said latch holding member from latch holding position to retracted position; and a releasing means for said power means operative to cause operation of said power means whereby said nut member will be rotated and said latch holding member will be retracted.

12. In an apparatus of the class described, for delivering a charge of material into a well, the combination of: a reservoir for said material having an opening at the lower end thereof; a tubular member extending downwardly from the lower end of said reservoir; a valve member in the upper part of said tubular member adapted to be moved into a position for closing said valve

opening of said reservoir; latch means adapted to be moved outwardly from said valve member into engagement with said tubular member to hold said valve member in raised position; a latch holding member having a latch holding position wherein it holds said latch means in engagement with said tubular member and a retracted position wherein it releases said latch means, said latch holding member having a threaded part projecting downwardly therefrom; a nut member engaging said threaded part; power means operative to rotate said nut member whereby to move said latch holding member from latch holding position to retracted position; and means operative to cause the operation of said power means, whereby said nut member will be rotated and said latch holding member will be moved into retracted position. 5 10 15

GEORGE H. ENNIS.
